VENTILATED CORSET

Pierre Amyot, Quebec, Quebec, Canada

Application May 27, 1943, Serial No. 488,711

3 Claims. (Cl. 2—34)

The object of this invention is to provide improved ventilating means for use in ventilated corsets of the type disclosed in Canadian Patent No. 227,674, granted Jan. 9, 1923.

The ventilating means shown in said patent comprises a series of separately formed, horizontally extending members connected between spaced vertical edges of two panel sections located at the back of the corset, said members being spaced vertically from each other and having their central portions secured in place between front and rear supporting strips which lie between the back panel sections and are spaced therefrom. This arrangement provides two rows of ventilating openings at opposite sides of the supporting strips to which the horizontally extending members are secured and constitutes a slightly and otherwise advantageous ventilating attachment.

Corsets provided with ventilating attachments constructed and applied as described above have proven eminently satisfactory in service but the cutting out of the component parts of the ventilating attachment and the assembly of these parts with each other and with the back panels of the corset has, in view of the time and number of operations involved, represented a considerable item of manufacturing expense. Nevertheless, the same method of constructing and assembling the component parts of this type of ventilating attachment is still being practiced by manufacturers since none of the cheaper substitutes heretofore proposed have been found sufficiently satisfactory in appearance and other essential respects to warrant their adoption.

The present invention provides a ventilating attachment which, while preserving the same general appearance and all other essential characteristics and advantages of the ventilating attachment shown in said patent, is designed so that it may be produced by a much simpler and cheaper method of manufacture.

Another advantage of the ventilating attachment provided in accordance with the present invention is that it eliminates the necessity of using certain stiffening bones which are required in the case of the ventilating attachment shown in said patent.

The improved ventilating attachment provided by my invention may be briefly described as follows: It consists essentially of a strip of fabric which is die cut from the piece so that said strip presents a central portion provided with integral tabs projecting outwardly from its opposite longitudinal margins, said tabs being vertically spaced from each other. This strip is se-

cured in place between separated inner vertical edges of two back panel sections of the corset by sewing the outer ends of the tabs to said sections. In the preferred embodiment of the invention the previously mentioned strip is provided with a one-piece lining strip which is adhesively secured thereto and is of exactly the same configuration. This preferred embodiment therefore provides what may be termed a "laminated" strip including a facing strip and a lining strip, both of which may be conveniently formed by a die-cutting operation. Those edges of the panel sections to which the outer ends of the tabs are secured are preferably reinforced by stiffening bones extending substantially the full length of said edges, said stiffening bones being concealed by covering or binding strips which also serve to cover and conceal the secured ends of the tabs.

Proceeding now to a more detailed description 20 of the invention reference will be had to the accompanying drawing, in which—

Fig. 1 is a back view of a corset showing the manner in which my improved ventilating attachment is secured in place between adjacent 25 separated edges of two back panel sections.

Fig. 2 is a transverse sectional view taken substantially along the line 2—2 of Fig. 1.

Fig. 3 is an elevational view of the ventilating attachment per se.

Fig. 4 is a transverse sectional view taken substantially along the line 4—4 of Fig. 3.

Fig. 5 is a fragmentary view of the back portion of a corset equipped with a slightly modified form of my improved ventilating attachment; and

Fig. 6 is a fragmentary vertical sectional view of the modified ventilating attachment shown in Fig. 5, the plane of the section being substantially along the line 6—6 of Fig. 5.

In Fig. 1 of the drawing my improved ventilating attachment is generally indicated at 5 and is shown secured in place between spaced inner vertical edges of two panel sections 6 which form the back of the corset 7. So far as the present invention is concerned the front and side panels 45 of the corset may be constructed in any conventional or desired manner and, therefore, need not be specifically described herein.

The ventilating means 5 comprises a one-piece shaped fabric strip 9 which is cut from the piece 50 (preferably by a die-cutting operation) so that it presents a relatively long and narrow central portion 10 and a plurality of integral, vertically spaced tabs 11 extending outwardly from each side of said central portion. The tabs 11 of each row are here shown as rectangular tabs spaced

from each other a distance substantially equal to their width. The strip 9 is preferably provided with a one-piece lining strip 12 which has exactly the same configuration and is preferably cut from the piece by a die-cutting operation. The facing strip 9 and the lining strip 12 are glued together and conjointly provide a "laminated" strip which is thick enough to have a substantial degree of stiffness. This "laminated" strip is secured in place, as shown in Figs. 1 and 2, by sewing the extreme outer ends of the tabs 11 to the inner sides of the opposing edges of the panel sections 6, the sewn ends of the tabs being preferably covered and concealed by binding strips 14. The edges of the panels 6 to which the "laminated" ventilating strip is thus secured are preferably reinforced throughout substantially their entire length by stiffening bones 15 which are preferably interposed between the binding strips 14 and the underlying ends of the tabs 11.

The facing and lining strips 9 and 12 of the "laminated" strip shown in Figs. 1 to 4 inclusive may be formed by separate die-cutting operations, following which the two strips are cemented together in properly assembled relation. It is preferred, however, that the facing and lining strips be shaped by a single die-cutting operation after these strips have previously been cemented together. This can be accomplished, for example, by cementing a sheet of facing material to a sheet of lining material and then cutting the shaped ventilating strips from this "laminated" sheet by a single die-cutting operation.

The construction shown in Figs. 5 and 6 is the same as that previously described except that the facing strip 9 is made of cord stiffened fabric in which the stiffening cords 17 run in the horizon-

tal direction when the ventilating attachment is secured in place. The cord stiffened fabric here referred to is preferably of the type described in U. S. Patent No. 2,096,835, granted Oct. 26, 1937.

5 Having thus described what I now conceive to be the preferred embodiments of this invention, it will be understood that various modifications may be resorted to within the scope and spirit of the appended claims.

10 Having thus described my invention, what I claim is:

1. In a corset a ventilating attachment comprising an elongated strip of material presenting a continuous central portion having its opposite side edges configured to provide a plurality of vertically spaced integral tabs extending outwardly from said central portion at intervals for attachment to the corset and providing openings therebetween.

20 2. In a corset a laminated ventilating attachment comprising a facing strip and a lining strip adhesively secured to the back of the facing strip throughout their contacting areas, each of said strips comprising a single piece of fabric shaped along opposite side edges thereof to present a relatively long and narrow central portion and a plurality of integral vertically spaced tabs extending outwardly from each side of said central portion.

25 3. A ventilating attachment for corset as set forth in claim 1, in which said strip and its integral tabs are composed of cord-stiffened fabric in which the stiffening cords are laid so that they extend horizontally across the strip and tabs when the latter is incorporated in the corset in the prescribed manner.

PIERRE AMYOT.
